DESIGN.

D. G. MELVILLE.

CARPET.

No. 16,554.

Patented Mar. 2, 1886.

UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 16,554, dated March 2, 1886.

Application filed December 18, 1885. Serial No. 186,092. Term of patent 3½ years.

To all whom it may concern:

Be it known that I, DAVID G. MELVILLE, of Medford, in the county of Middlesex and State of Massachusetts, have invented a certain new and original Design for Carpets, of which the following is a specification.

The nature of my design is fully shown in the accompanying photographic illustrations.

The design is composed of the variously-shaped figures and the floral and foliage ornamentation shown.

The leading features of the design are the said variously-shaped figures and floral and foliage ornamentation, said figures having mottled central portions and darker borders, 15 as shown, and being partly covered by the foliage ornamentation.

I claim—

The design for a carpet, substantially as shown and described.

In testimony whereof I have signed my name to this specification, in the presence of two subscribing witnesses, this 14th day of December, 1885.

DAVID G. MELVILLE.

Witnesses:

THOMAS J. STEARNS,

DAVID McNAIR.
